UNITED STATES PATENT OFFICE

HOWARD S. HART, OF NEW BRITAIN, CONNECTICUT, ASSIGNOR TO HART & COOLEY MANUFACTURING COMPANY, OF CHICAGO, ILLINOIS, A CORPORATION OF DELAWARE

REGISTER AND VENTILATOR

Application filed November 9, 1929. Serial No. 405,876.

This invention relates to certain new and useful improvements in registers and ventilators, and particularly to such registers as rest against the side wall of the room.

- 5 The object of the invention is to construct a simple and effective means to provide a tight fit between the register and the side wall for the purpose of preventing any dust laden air which comes up from the furnace 55
10 from escaping around the edge of the register and "streaking" the wall. It is seldom indeed that the side wall of a room is made so accurately that the ordinary register will fit so uniformly against the same as to make 60
15 a sufficiently tight joint to prevent dust laden air from escaping and the consequent "streaking" of the wall. Consequently, it is the purpose of my invention to provide 65
means to prevent this.
20 In the accompanying drawing I have shown my invention as embodied in a so-called base-board register; that is to say, a register that is fitted against the side wall at the base, the lower edge of the register 70
25 resting on the floor, but, as will be obvious, the invention is applicable to any form of side wall register whether the same be located at or above the base.

In the drawings—

- 30 Fig. 1 is a front elevation of a base-board register as it would appear in place;

Fig. 2 is a rear elevation of the register frame detached, the center perforated panel being removed and part of the packing being removed;

Fig. 3 is a relatively enlarged cross-section on the line 3—3 of Fig. 1.

- 1 represents the frame of the register which has a rearwardly directed flange 2 around 40 its outer edge which is designed to bear against the wall 3. 4 represents a base-board. Within the central part of the frame is located a plate perforated in any desired manner to allow hot or cold air to pass therethrough. In the form shown, this center plate is indicated at 5, and is provided with long, vertical, closely arranged slotted openings. The number, size and shape of these 45 openings may be varied as desired, and the

center plate may be separate or integral with the frame 1 as desired. The frame 1 is also provided with a relatively short rearwardly directed flange 6 which is designed to fit into the air duct 7, which is usually of tin, and is located in the wall opening in position to receive the register. It is seldom indeed that such a close fit can be made between the flange 6 and the air duct 7 that air passing through the duct toward the register will not leak around the flange 6. In Fig. 3 I have shown a slight space such as will almost invariably be found to exist somewhere between the flange 6 and the duct 7. Thus, air escaping through this space will, unless prevented, continue on and escape past the flange 2 and cause a "streaking" of said wall. It is the purpose of my invention to provide simple and effective means to prevent this "streaking". To that end I provide a yieldingly mounted, relatively soft pad or the like 8 just adjacent the flange 2 where it bears against the wall which is so designed that it will yieldingly press against the wall 3 to form a sufficiently tight joint or packing to prevent air escaping past the flange 2. In the particular form shown, the pad 8 may be made of thick felt and may be mounted on a yielding or spring-like support 9 which is secured in any desired manner, as by solder, to the inside of the flange 2 the packing edge of said support being spaced away from said flange. The pad 8 may be secured to its support 9 in any desired manner as by rivets 10. The support is so formed that it will hold the packing pad normally in such position as to press with reasonable snugness against the wall 3 when the register is secured in place, said pad being provided wherever there is danger of leakage past the flange 2 so as to cause "streaking" of the wall. The register may be secured in place by any desired means such as by screws 11—11, which may pass through the frame 1 and through openings or passages 12 in the pad supporting means, the screws themselves passing on into the studding indicated at 14, this being one com- 55

mon means employed for the securing of side wall registers in place.

While I have described my invention in one preferred form, I wish it understood that various modifications and arrangements can be made from that shown herein without departing from the spirit of the invention or the scope of the following claims.

What I claim is:

- 10 1. In a side wall register, a frame constructed at its outer edge to rest against the side wall, a yielding packing adjacent to the wall bearing edge of said frame, and yielding means for supporting said packing.
- 15 2. In a register, a frame, a flange at the outer edge of said frame, another flange at the inner edge of said frame, a packing between said flanges and at the rear of said frame, and a yielding support for said packing.
- 20 3. In a register, a frame, a flange at the outer edge of said frame, another flange at the inner edge of said frame, a yielding packing between said flanges and at the rear of said frame, and a yielding support for said yielding packing.
